DISPENSING CONTAINER AND CLOSURE
THEREFOR

Henry E. Van Ness, Elmira, N. Y.

Application June 6, 1934, Serial No. 729,167

8 Claims. (Cl. 221—60)

This invention relates to an improved dispensing container, and more particularly to a closure therefor.

Dispensing containers for toothpaste, shaving cream and the like have heretofore been made by forming a thin metal tube having a neck and externally threading the neck to receive an internally threaded cap. A gasket is ordinarily placed inside the cap to insure a tight seal when 10 the cap is screwed onto the neck of the tube.

Such tubes are ordinarily formed by a punch and die operation, the body of the tube being extruded through a small circular opening surrounding the punch. When the tube is punched out, the end of the punch retains a thin wall 15 of metal between its end and the bottom of the die which constitutes a thin metal partition, closing the upper end of the neck of the tube.

After the extrusion of the tube, the first steps 20 in the manufacturing procedure heretofore ordinarily employed are (1) to open the closed end of the neck of the tube, (2) to roll a thread on the exterior of the neck of the tube, and (3) to screw an internally threaded cap containing a 25 gasket onto the neck of the tube. Ordinarily, the neck of the tube is threaded for some distance, and to properly seat the cap thereon it is necessary to turn the cap several times. The tubes are thereafter enameled, labeled, baked 30 and filled from the rear end which is then sealed.

In my simplified container, instead of the customary internally threaded cap, I use a cork or stopper with an externally threaded plunger adapted to be inserted in the neck of the tube. 35 When the diaphragm closing the top of the neck of the tube is opened, a flange is left around the lip of the neck. The thread on the stopper engages this flange, and I have found that it is only necessary to turn the stopper through 40 part of a revolution in order to seat it firmly in the neck of the tube. To facilitate the seating of the stopper, I form the closed end of the neck of the tube with a helical concavity adapted to engage the lowest turn of the thread on the 45 stopper and position it correctly for insertion in the neck of the tube.

In one embodiment of my invention, I have provided a stopper with a conically shaped plunger having a point by which the closed end 50 of the neck of the tube may be readily punctured when the stopper is initially seated in the neck of the tube. In the manufacture of this embodiment of my container, the top end, or neck, of the tube may be left in the condition in which 55 it is originally formed, the stopper being pro-

vided with the filled tube and inserted by the user. Even if the stopper is inserted by the manufacturer, my invention, in addition to eliminating the need for a gasket, simplifies the method of manufacture by combining the heretofore separate steps of opening the closed end of the tube and assembling a cap thereon, and eliminates the operation of rolling a thread on the exterior of the neck of the tube.

In another embodiment of my invention, I have provided means in conjunction with the stopper for preventing the stopper from being altogether detached from the tube without limiting or interfering with the necessary movements 15 of the stopper. With this form of my invention, it is necessary to open the closed end of the neck of the tube, as has heretofore been done, but the gasket heretofore used with the internally threaded caps and the operation of rolling a thread on the exterior of the neck of the tube 20 are both eliminated.

Other objects and advantages of my invention will appear from the following description and the claims appended thereto, and the invention will best be understood if read in connection with 25 the accompanying drawing, in which:

Fig. 1 is a top plan view of the tube before the top end of the neck is punctured;

Fig. 2 is a cross-section taken on the line 2—2 of Fig. 1;

Fig. 3 is a cross-section taken on the line 3—3 of Fig. 1;

Fig. 4 is a view partly in cross-section showing the closed end of the neck being punctured by the 35 pointed cork or stopper;

Fig. 5 is a top plan view of the tube after the closed end of the neck has been punctured;

Fig. 6 is a view partly in cross-section of the stopper shown in Fig. 4, seated in the neck of the tube after the closed end has been punctured;

Fig. 7 is a view partly in cross-section of a modified form of closure;

Fig. 8 is a view of the closure shown in Fig. 7, with the stopper removed from the neck of the tube; and

Fig. 9 is a view partly in cross-section of a modified form of closure.

The tube 1 has a neck portion 2 which, as originally formed, is closed at the top by a thin diaphragm 3. On its external surface, the diaphragm 3 has a central depression 4 surrounded by a helical concavity 4a which, starting at the point x on the top of the shoulder 4b, increases in depth until it reaches the point y at the bottom of the shoulder 4b. The inclination of the 55

helical concavity $4a$ corresponds to the helix angle of the thread 5 on a cork or stopper adapted to be inserted in the neck of the tube. It will be seen that the concavity $4a$ is formed around the lip of the neck 2 of the tube, and after the diaphragm 3 has been opened this concavity, by receiving the lowest portion of the thread 5 on the stopper, positions the stopper so that it will be screwed in straight.

10 In Figs. 4 and 6, I have shown a cork or stopper 6 having a conically shaped plunger 7 , and in Figs. 7 and 8 I have shown a modified form of cork or stopper 10 having a plunger 9 in the form of a truncated cone. After the diaphragm 3 has been opened, the thread 5 of the stopper is engaged by the flange $3a$ of the lip of the neck of the tube constituted by the remaining edge of the diaphragm 3 , and this is true whether the stopper 6 shown in Figs. 4 and 6, or the stopper 10 shown in Figs. 7 and 8, is used. Only a partial turn of the stopper is required to seat it tightly in the mouth of the tube.

When the stopper 6 is used, the diaphragm 3 closing the upper end of the neck of the tube 2 may be readily punctured by the pointed end of the plunger 7 , as shown in Fig. 4, and, by further rotation of the stopper, it may be firmly seated in the neck 2 of the tube as shown in Fig. 6.

When the stopper 6 is used, it will not be necessary for the manufacturer to initially open the diaphragm 3 closing the upper end of the neck of the tube, but instead, the stopper may be simply supplied with the tube with directions for the user to puncture the diaphragm 3 there-with preparatory to using the contents of the tube.

In the modified form of my invention illustrated in Figs. 7 and 8, the stopper 10 is similar to stopper 6 , except that the plunger 9 is in the form of a truncated cone. Secured to the plunger of the stopper 10 is a wire 11 , the coiled end $11a$ of which is sprung within the body of the tube 1 . While the coiled end $11a$ prevents the member 11 from being withdrawn through the neck of the tube, it does not prevent the stopper from being freely rotated, and also permits a limited withdrawal of the member 11 so that the stopper 10 may be moved out of line with the open mouth of the neck 2 of the tube to permit the material contained by the tube to be discharged. This form of my invention has the advantage of preventing the stopper from being completely disassociated from the tube, thereby preventing the stopper from becoming lost or misplaced.

55 In the drawing, Figs. 4, 6, 7 and 8, I have shown a stopper or cork having a circular top with a comparatively narrow flange below which extends the tapered plunger. I have illustrated this simple form of stopper in order to emphasize the fact that it has an externally threaded plunger. However, I contemplate using a stopper such as is illustrated in Fig. 9, the top portion 15 of which, instead of being circular, may be polygonal, preferably hexagonal in form, and in which the flange $15a$ of the top portion will extend downwardly approximately the same distance as the externally threaded plunger 16 . This structure gives protection against possible injury which might otherwise be received from the pointed end of the plunger, for example, if the stopper is dropped on the floor and stepped upon. The stopper having the polygonal top and flange portion has the added advantage of

not rolling when laid down and is convenient to handle.

What I claim is:

1. In combination, a dispensing container comprising a stopper having a helical, external thread, a tube with a hollow neck having an internal annular lip at its outer end, the lip of said neck having a shoulder and a helical concavity inclined from the top to the bottom of said shoulder and adapted to engage said thread. 10

2. In combination, a pointed stopper having a helical, external thread, a tube having a hollow neck to receive said stopper, said neck having its upper end closed by a thin partition until it is opened by insertion of the stopper in said neck, 15 and an internal lip on said neck provided with a helical concavity corresponding with the helix angle of the external thread on said stopper and adapted to engage said thread.

3. In combination, a dispensing container 20 comprising a pointed externally threaded stopper, a tube with a hollow neck closed at its upper end prior to the insertion of the stopper therein, and an internal lip at the closed end of the neck having a shoulder and a helical concavity inclined from the top of said shoulder around the lip of the neck to the bottom of said shoulder, the angle of said incline corresponding with the helix angle of the thread on said stopper. 25

4. A closure for dispensing containers, comprising a tube having a hollow neck closed at its upper end by a diaphragm having a depression at its center surrounded by a helical concavity, and a stopper having a pointed end adapted to puncture the center of said diaphragm and having an external thread adapted to engage the said helical concavity in said diaphragm. 30

5. In combination, a tube having an open-ended neck provided with a helical concavity, a stopper insertable therein having a helical external thread adapted to engage said concavity, and a wire, one end of which is secured to said stopper and the other end of which is retained within the tube in such a manner that the wire is capable of free rotary movement or limited 45 axial movement with respect to the neck of said tube.

6. In combination, a tube having an open-ended neck provided with a helical concavity, a stopper adapted to be seated in said neck and having a 50 helical, external thread adapted to engage said concavity, and means interconnecting the stopper and the tube in such a manner that the stopper is freely rotatable and capable of a limited movement away from said tube. 55

7. In combination, a dispensing container, comprising a stopper having a tapered externally threaded plunger and a polygonal flange surrounding said plunger, a tube with a hollow neck having an internal lip at its outer end, the flange of said stopper being sufficiently spaced from the plunger to receive the neck of said tube there-between, the lip of said neck having a helical concavity inclined at an angle corresponding to the helix angle on the thread of said stopper. 60 65

8. A dispensing container comprising the combination, with a tube having a neck with a lip provided with a helical concavity, of a stopper for said tube having a helical, external thread inclined at an angle corresponding to the helix 70 angle of, and adapted to engage, said concavity.
